MATTHEW M. MERRITT, OF MIDDLETON, MASSACHUSETTS, ASSIGNOR TO BOSTON INCANDESCENT LAMP COMPANY, OF DANVERS, MASSACHUSETTS, A CORPORATION OF MASSACHUSETTS.

PROCESS FOR EXHAUSTING LAMPS.

No. 809,811.

Specification of Letters Patent.

Patented Jan. 12, 1909.

Application filed January 27, 1905. Serial No. 242,846.

To all whom it may concern:

Be it known that I, MATTHEW M. MERRITT, a citizen of the United States, residing at Middleton, in the county of Essex and State of Massachusetts, have invented an Improvement in Processes for Exhausting Lamps, of which the following description, in connection with the accompanying drawings, is a specification, like letters on 10 the drawings representing like parts.

My invention relates to the manufacture of incandescent lamps, and consists more particularly in a new process of employing a chemical assistant in the exhaustion of the bulb.

The process of lamp exhaustion, as heretofore carried out, has consisted generally in exhausting the bulb to some selected point by means of a vacuum pump. The 20 pump is then cut off from the bulb and the filament brought to a state of high incandescence by the passage of an abnormal current therethrough to expel the gases absorbed in the filament and the joints thereof 25 and at the same time suitable chemical substances are permitted to act upon the deleterious gases, and particularly the oxygen, remaining within the bulb. The object of this is the conversion into harmless 30 pounds of those gases which remain after mechanical exhaustion in the highly rarefied atmosphere of the bulb and would be injurious to the life or efficiency of the filament. This process of chemical exhaustion 35 has been well-known in the art for many years. More recently, this process has been practiced by inserting the chemical agent in the open ended tubulature which it is customary to secure to the tip of the bulb 40 about to be exhausted. This tubulature having been connected with the pump and exhaustion carried to the required degree, which is naturally short of the final vacuum, communication is interrupted between the 45 pump and the tubulature below the chemical. The lamp filament is then brought to intensive incandescence and simultaneously the chemical in the tubulature (if, as usual, a volatile chemical is employed) is heated to cause it to unite with the occluded gases of the bulb and the deleterious gases driven from the carbon of the filament and the joints. As soon as chemical union has taken 55 place, which is determined by the visual dis- appearance of an intensely blue or violet

colored glow within the bulb, the latter is sealed off from the tubulature above the chemical, the lamp then being in a practically finished state.

The process of introducing a chemical agent into the tubulature has material defects. The procedure involves starting the chemical action by a violent heating of the tubulature before the sealing off of the bulb. It is difficult even for an experienced operator satisfactorily to volatilize the chemical in the tubulature without occasionally so overheating the walls thereof, and particularly at its slender neck where it is joined to the bulb, as to form a slight crack or fissure 60 with the consequent admission of air. It has been found that if even a slight amount of air is admitted before the chemical action is completed, the vacuum is not only destroyed or impaired, but the chemical action 65 is accompanied by the production of a brownish yellow deposit on the interior of the bulb which makes the lamp defective and unsalable. It is a frequent occurrence in carrying out the process described to 70 overheat the tubulature while volatilizing the chemical and permanently discolor the bulb. This procedure also involves the somewhat hurried sealing off of the bulb from the tubulature while the chemical action 75 is at its height. This hasty sealing of the bulb is often accompanied by the formation of a slight crack at the seal, or the admission of a small amount of air before the seal is perfected, which results as above in 80 spoiling the lamp and in impairing or destroying the vacuum. After completion of 85 mechanical exhaustion and before the chemical action takes place, much of the remnant gaseous matter is in the form of moisture. This becomes apparent to the eye in the 90 form of an illuminated fog-like haze before the filament is brought to intensive incandescence, which haze hovers about the narrow opening between the tubulature and the bulb. Under the process referred to, it is 95 extremely difficult to properly extract this moisture. For some reason, it tends to seal the narrow opening of the tubulature and prevent the entrance of the volatilized chemical into the bulb, while at the same time the volatilized chemical tends to prevent the moisture from leaving the bulb. Even if the 100 pump is kept in communication with the bulb during a preliminary heating of the chem- 105

ical and filament, the pump tends to suck the chemical out of the tubulature while extracting the moisture in the bulb only with the greatest difficulty. This trouble is also enhanced by the fact that the tubulature through which or into which the moisture should pass, is raised to a high heat tending to drive back the moisture into the bulb. The final sealing of the lamp which is performed after interrupting communication with the pump also tends to drive any attracted or absorbed moisture in the tubulature out of it and into the rapidly cooling and relatively cooler bulb.

15 Prior to the exhaustion process the bulb is customarily heated in an oven to drive off the absorbed moisture and gases. Unless the exhaustion is effected rapidly, however, the subsequent cooling of the bulb causes a material re-absorption of those gases. Again, if the filament is raised to intensive incandescence without the presence of the volatilized chemical the expelled gases tend to unite with the hot filament greatly to its detriment. It is difficult to perform the present process rapidly enough to prevent a material cooling of the bulb, and, owing to the remoteness of the chemical from the filament and the check which the expelled moisture 20 puts upon the entrance of the chemical into the bulb when the filament is raised to intensive incandescence, a large portion of the expelled gases undoubtedly combine with the highly heated filament, burning and blackening the same.

30 My process provides an entirely novel and different mode of performing the exhaustion of the lamp, whereby it can be completed with fewer steps and in less time than with the present process, being at the same time free from the defects above pointed out.

40 My process will be best understood by reference to the following description, wherein, for illustrative purposes, there is given in detail the preferred mode of performing it, while its scope will be more particularly pointed out in the appended claims.

45 The drawing shows diagrammatically a lamp bulb *a* with its contained filament *b* and the attached tubulature *c*, all of which are typical of a lamp of the usual construction. The end of the tubulature is shown inserted in a rubber socket connection *d*, which is in communication with an air pump 50 (not shown). The latter may be of any description capable of exhausting to the degree required as a preliminary for the chemical action.

55 Preferably within the normal bulb space, instead of in the tubulature as before, and preferably, although not necessarily, upon the inner walls of the bulb itself, as at *e*, there is deposited a small and preferably definite amount of some one of the well-known agents suitable for chemical exhaustion,

60 such, for example, as red amorphous phosphorus. The location of the chemical shown in the drawing, is particularly advantageous, for it is in immediate proximity to the porous pasted joints of the filament wherein are absorbed the major portion of the deleterious gases finally expelled. The insertion of this chemical (which in the drawing is shown greatly exaggerated in amount) is effected at some prior stage 65 in the process of the lamp manufacture and may be conveniently accomplished before the tubulature is joined to the bulb. The lamp having been previously warmed or heated, as in an oven, to drive out as large a portion as possible of the absorbed gases, 70 its tubulature is connected with the pump, as shown in the drawing, and there remains for a few moments until mechanical exhaustion to the required degree has been 75 accomplished. Meanwhile the filament may be made to glow slightly by the passage therethrough of a current of normal or somewhat less than normal strength. This point having been reached, I then preferably bring the filament to intensive incandescence and at the same time heat the glass bulb, and particularly at the point *e* where lies a deposit of chemical, the connection 80 with the pump, however, preferably remaining uninterrupted. This volatilizes a portion of the chemical already within the bulb, causing it to act, not only upon the residual gases of the bulb space, but also upon the expelled gases from the filament and the 85 joints thereof and the gases driven out from the pores of the bulb, these gases, however, being freed in the immediate presence of the volatilized chemical and having no opportunity to unite chemically with the filament. The heat applied to the bulb to volatilize the chemical also materially assists in 90 expelling the absorbed gases. During this operation the pump easily withdraws the moisture discharged from the filament and the bulb through the free open passage of the tubulature which is obstructed by neither volatilized nor unvolatilized chemical. As soon as the moisture has been withdrawn 95 and before the chemical has been completely volatilized, the lamp is sealed between the bulb and the tubulature at *f*, such sealing hermetically closing both the bulb and the tubulature, which latter remains in the socket. The chemical remaining within the 100 bulb, which latter is now in its complete, hermetically-sealed state, is then again heated to complete its volatilization and the filament simultaneously brought to intensive incandescence. This operation will be 105 accompanied first by the appearance and then the disappearance of the blue glow referred to, which will indicate the completion of the exhaustion of the lamp. The severed and sealed tubulature may remain 110

in its socket until a fresh lamp is to be exhausted, when it may be replaced by the tubulature attached thereto. It will be seen that the final step of this process of exhaustion, as here performed, is the chemical action upon the atmosphere of the bulb after the latter is hermetically sealed in its completed state and after every step which can in any way affect the vacuum therein has been performed. This absolutely avoids the possibility of any air or gases entering into the bulb during the final chemical action. It also permits this final chemical exhaustion to be carried on carefully and, if desired, leisurely. In fact, any desired interval may elapse between the time of sealing of the bulb and the time of volatilizing the remaining chemical in the presence of the incandescent filament.

The present process requires the placing of an amount of chemical in the tubulature largely in excess of what is required for the actual chemical action which takes place. This is not only detrimental because the chemical absorbs and retains a considerable quantity of moisture, but more particularly because it is difficult or impossible for the operator to volatilize just the precise amount needed for the required chemical reaction. This required amount is a definite quantity and if exceeded will result in a discoloration of the bulb similar to that produced when air is admitted in excess through an accidental crack or fissure, as above described. The use of an excess amount of chemical, however, is a necessary consequence of its volatilization in the tubulature, for it is volatilized at a point comparatively remote from where it is needed and an indeterminate portion of it undoubtedly fails to enter the bulb at all. By my process, the amount of chemical can be reduced to substantially that which is required for the chemical action, this being a definite proportion which can be easily determined in each case. When this is volatilized it may be known that the action is complete and it is impossible for the operator to discolor the bulb by the volatilization of an excess amount of chemical as is the case in the present process.

It is to be observed that in my process the restricted entrance to the tubulature and the tubulature itself may be maintained in free communication with the pump up to the

moment of sealing the bulb, so that all moisture and gaseous matter which it is possible for the pump to withdraw will be withdrawn without interference or opposition on the part of the volatilized chemical. 60

The manipulation in my process is so simplified that it can be performed with greater rapidity, and with less opportunity for the cooling of the bulb. As has been observed, however, the latter is no serious defect in 65 my process for the heating of the chemical is accompanied by a heating of the bulb and the expulsion of the contained gases in the immediate presence of the chemical.

Other advantages, many of which will be 70 apparent to those skilled in the art, follow from the use of my process but these, as well as the many modifications thereof and the many variations in the detailed steps thereof are unnecessary to mention; it being understood that my invention is not limited to the details here described but only to the broad principles claimed. 75

Claims:

1. The process of exhausting lamp bulbs 80 which consists in inserting a volatile chemical agent within the bulb, placing the latter in communication with a pump, exhausting to the required degree, raising the filament to a state of incandescence and partially 85 volatilizing the said chemical while said bulb is still in communication with the pump, sealing off the bulb and thereafter completing the volatilization of the chemical in the presence of the incandescent filament. 90

2. The process of exhausting a lamp bulb which consists in placing the latter in communication with a pump, exhausting to the required degree, raising the filament to 95 a state of incandescence, acting upon the residual gases by a volatilized chemical agent while the bulb is still in communication with the pump, sealing off the bulb and thereafter acting upon the residual gases by 100 a volatilized chemical agent in the presence of the incandescent filament.

In testimony whereof I have signed my name to this specification in the presence of two subscribing witnesses.
